CLAIM

The ornamental design for a connector for signal transmission, as shown and described.

DESCRIPTION

FIG. 1 is a top perspective view of a connector for signal transmission;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is a bottom perspective view thereof.
